Primary Examiner — Lilyana Bekic(74) *Attorney, Agent, or Firm* — Schwegman Lundberg & Woessner, P.A.(57) **CLAIM**

The ornamental design for a nebulizer device, as shown and described.

DESCRIPTION

FIG. 1 is a perspective view of a nebulizer device in a closed state showing my new design;

FIG. 2 is a perspective view of the nebulizer device in an open state;

FIG. 3 is a front view thereof in the closed state;

FIG. 4 is a back view thereof;

FIG. 5 is a left view thereof;

FIG. 6 is a right view thereof;

FIG. 7 is a top view thereof; and,

FIG. 8 is a bottom view thereof.

Broken lines in the drawings depict portions of the nebulizer device that form no part of the claimed design

1 Claim, 8 Drawing Sheets(56)
